WELL PACKER LOCK DEVICE

Reuben C. Baker, Coalinga, and Thomas M. Ragan, Downey, Calif., assignors to Baker Oil Tools, Inc., Vernon, Calif., a corporation of California

Application July 20, 1946, Serial No. 685,023

15 Claims. (Cl. 166—12)

1

This invention relates to well devices, and more particularly to well packers adapted to be lowered within and anchored to well casings, liners, and similar conduits.

It is an object of the present invention to provide a lock arrangement capable of safely transmitting much greater loads between a well packer body and slip expander than heretofore possible, and of eliminating the tendency of the body to shift with respect to the casing in which the packer is anchored.

Another object of the invention is to provide a well packer whose body is anchored to a well casing through cooperable slips and an expander, and in which any tendency for the body to be rotated after setting of the well packer in the casing causes the slips to be embedded or engaged more firmly with the casing wall, thereby resisting the tendency of the body to rotate and facilitating its disintegration by a rotary drill bit.

Yet a further object of the invention is to provide a well packer lock device operable to expand packer slips into firm anchoring engagement with a well casing, and which also locks the well packer body against longitudinal movement.

Still another object of the invention is to utilize the engaging force between a well packer expander and its cooperable slips for locking the well packer body to the expander against longitudinal movement.

This invention has other objects that will become apparent from a consideration of the embodiments shown in the drawings accompanying and forming part of the present specification. These forms will now be described in detail to illustrate the general principles of the invention, but it is to be understood that such detailed description is not to be taken in a limited sense, since the scope of the invention is best defined by the claims appended hereto.

Referring to the drawings:

Figure 1 is a partly sectional and elevational view of a well packer in a well casing, with its parts in retracted position;

Figure 2 is a partial longitudinal section of the well packer in partly tripped position;

Figure 3 is a partial longitudinal section of the packer fully anchored in packed off condition within the casing;

Figure 4 is a perspective of the split lower tapered expander;

Figure 5 is a partial longitudinal section through a well packer, illustrating another embodiment of the invention; and

2

Figure 6 is a cross-section taken along the line 6—6 of Figure 5.

The invention is illustrated in the drawings as applied to a well packer of the general type shown in United States Patents Nos. 2,121,051, 2,189,703 and 2,222,014. Essentially, it consists of a central tubular body 10 secured to a string of tubing or drill pipe 11, by means of which it is lowered through a well casing 12 to the desired point at which it is to be anchored in packed off condition. The packer is anchored against movement in an upward direction by a set of upper segmental slips 13 initially held in retracted position by shear screws 14 threaded into a conical-like expander 15 slidable on the exterior of the body 10. This expander, whose outer surface 16 tapers in an upward and inward direction, to conform to the inner taper 17 on the slips 13, is also initially secured to the body by one or more shear screws 18.

Downward movement of the well packer is prevented by a plurality of segmental lower slips 19 having tapered surfaces 20 inclined downwardly and inwardly and adapted to slide along a companion external tapered surface 21 on the exterior of a lower conical expander 22 which is slidable on the body 10. The lower slips are initially held in retracted position by shear screws 23 securing them to the lower cone 22, and the lower cone is also held in an initial upward position with respect to the lower slips by one or more shear screws 24 secured to the body. The lower screws 23, 24 have a greater shear value than the upper screws 14, 18, for reasons hereinafter brought out.

A packing sleeve 25 is provided between the two expanders 15, 22, having external end flanges 26, 26 interlocking with inwardly extending flanges 27, 27 on the expander cones. The sleeve 25 is also provided with internal lip seals 28, 28 at its ends adapted to slidably seal with the external surface of the body 10.

The upper slips 13, when in retracted position, are contained within the circumferential confines of a trip ring 29 secured to the upper end of the body. Similarly, the lower slips 19 are contained initially within the peripheral confines of an abutment at the lower end of the body, defined by a valve housing and guide 30 threaded on a lower body flange 31. This valve guide 30 depends from the body 10, and has a tripping ball seat 32 secured in its lower end by a shear screw 33. An arm 34 extends upwardly from the seat to hold a buoyant back pressure valve ball 35 in effective position to one side of the passage 10b

through the packer body, in order to prevent its engaging a valve seat 36 at the lower end of the body while the tool is being lowered through the fluid in the well casing.

The tool is run in the well bore with the parts in retracted position, as shown in Figure 1. When the setting point is reached, a tripping ball 37 is lowered or pumped down through the tubular string 11 until it engages the trip ball seat 32, closing the passage 10b against flow of fluid therethrough. Pressure can then be built up in the tubing string and body to force fluid under pressure through lateral ports 38 in the body into the elastic packing sleeve 25, inflating the latter against the casing and then elongating it in an upward direction to shear the screws 18, 14 holding the upper expander 15 to the body and the upper set of slips 13 to this expander. Such upward movement of the cone 15 causes it to move within the slips 13 and forces the latter radially outward along the abutting trip ring 29 into engagement with the casing 12 (see Figure 2). The tubing string 11 and connected packer body 10 are then elevated to move the body, lower slips 19 and lower cone 22 upwardly with respect to the upper expander 15 and slips 13, foreshortening or compressing the packing unit 25 in a longitudinal direction and thereby expanding it outwardly against the casing to form a leak-proof seal between the body and casing.

After the packing has been thus engaged with the casing, a continuation of the upward strain and movement on the packer body 10 shears the screws 24, 23 holding the lower expander 22 to the body and the slips 19 to the expander 22, the lower abutment 30, 31 shifting the slips 19 longitudinally in an upward direction along the outer surface 21 of the expander and radially into anchoring engagement with the casing 12 (see Figure 3). Such action occurs because the lower expander 22 is prevented from moving upwardly by the casing engaging upper slips 13 and sealed off packing 25. It is to be noted that the wickers 13a on the upper slips 13 face in an upward direction and the wickers 19a on the lower slips in a downward direction, preventing upward movement of the upper cone 15 and downward movement of the lower cone 22, and also precluding shifting of the intervening packing 25.

After both sets of slips have been firmly anchored to the casing, the packer body 10 is incapable of moving in an upward direction because of the engagement of its abutment 30, 31 with the lower slips 19, and a transmission of such upward force through the lower slips 19, lower expander 22, packing member 25, upper expander 15 and upper slips 13 to the wall of the casing 12. Downward movement of the packer body 10 is prevented by a one-way type of locking arrangement between the body, expander and slips.

As shown in the drawings, the downwardly acting lock is provided by the body 10, cone 22 and slips 19 themselves. In the Figure 1 embodiment of the invention, the lower portion of the lower conical expander 22 is separated into segments 39 by spaced longitudinal extending slots or saw cuts 40 running from the narrow lower end of the expander and terminating just short of the expander portion receiving the packing flange 26, providing an arrangement in which the segments 39 of the slotted expander are held together by the expander flange portion 27. The

segments thus formed have sufficient resiliency to permit their lateral movement to the slight extent necessary into and out of engagement with the exterior of the body. Initially, when unrestrained, the internal diameter of the expander is slightly greater than the external diameter of the body. However, the segments 39 are urged inwardly toward the body 10 upon exertion of a downward thrust on the latter member by a slight downward movement of the expander 22 within the slips 19 anchored to the casing 12. The cooperable tapered surfaces 21, 20 between the expander and slips cause forcing of the expander segments 39 inwardly into firm gripping engagement with the body 10; and the greater the downward force on the body, the greater is the wedging of the expander segments into the slips 19 and their inward forcing against the exterior of the body.

For the purpose of preventing potential slipping between the body 10 and split expander 22 upon downward movement of the former with respect to the latter, the exterior of the body is preferably formed with downwardly facing wickers or teeth 41 engageable with companion wickers or teeth 42 on the inner face of the expander segments 39. The teeth are so arranged as to permit upward movement of the packer body 10 within the lower expander 22 for the purpose of releasing the lower slips 19 from retracted position and moving them along the lower expander into anchoring engagement with the casing wall. However, subsequent downward movement of the packer body produces its positive clutching engagement with the expander segments 39 and wedges the latter firmly into the slips 19, which, reactively, force the expander segments inwardly of the body to prevent any possibility of disengagement between the body and expander teeth 41, 42.

For simplicity and economy of manufacture, the ratchet teeth 41, 42 around the body and in the cone may be formed as a buttress type of thread, having the same pitch. The ratchet teeth are also preferably formed as a left hand thread. This is highly desirable since the subsequent drilling out of the well packer by a rotary drill bit may be facilitated thereby.

Substantially all of the packer parts are preferably made of readily drillable material, such as cast iron, aluminum or magnesium, to allow ready removal of the well packer from the casing under the disintegrating action of a drill bit. For more effective operation of the drilling tool, the parts to be disintegrated should be held from rotating with the bit. The provision of the left hand thread interconnection 41, 42 between the packer body 10 and lower conical expander 22 tends to hold the body stationary under the action of a right hand rotating drill bit. Any tendency for the body to rotate in a right hand direction tends to feed the lower expander 22 downwardly into much firmer wedging relation with the slips 19 and the body 10, the slips being urged against and into the casing 12 with greater force, thus precluding turning of the body.

The threaded connection 41, 42 also possesses the advantage of holding the body against rotation during unscrewing of the tubing string 11 from the body 10 after the packer has been set in the casing and performed its required function. The connection between the tubing string and packer body is usually a left hand thread 50, whose disconnection is effected by right hand rotation of the tubing string 11. Such right hand

rotation tends to rotate the packer body in a right hand direction as well. In view of the left hand thread 41, 42 between the body 10 and lower expander, right hand body rotation tends to elevate the body, which cannot take place because of the abutting of the lower end of the body 31 with the lower slips 19, and the solid connection between these slips 19 and the upper casing anchored slips 13 through the lower expander 22, packing 35 and upper expander 15. As a result, any right hand rotary movement of the body 10 could only feed the expander 22 downwardly into firmer wedging engagement with both the lower slips 19 and body 10.

The embodiment of invention disclosed in Figure 5 provides an arrangement in which the segments 43 of the split lower conical expander 44 are completely separated from one another, being capable of moving bodily radially into coupling or clutching engagement with the left hand threaded wickers or ratchet teeth 41 on the body 10, to insure that the entire length of the teeth 42 on each segment 43 is in full engagement with the companion teeth 41 on the body. These segments are coupled for joint longitudinally relative to the body 10 and slips 19 by a coupling ring or sleeve 45, which may be connected to the lower end of the packing 25 in substantially the same manner as the expander 22 of the other form of invention is coupled to the lower end of its cooperable packing 25. The connection between the expander segments 43 and coupling ring 45 is effected by providing an internal ring groove 46 receiving an external flange 47 at the upper ends of the expander segments, and by the corresponding reception of an internal flange 48 on the ring in an external circular groove 49 formed collectively in the segments 43 below their external flange 47. This connection causes the expander segments 43 and coupling ring 45 to move in unison longitudinally, while permitting the slight amount of free radial movement of the expander segments with respect to the body 10 in being uncoupled from the body, during its upward movement, and firmly and positively coupled to the body upon its downward movement, which carries the conical expander segments 43 downwardly into the slips 19 and radially inward, because of the wedging action produced by the cooperable tapered surfaces 21, 20 on the expander segments and slips.

As in the other embodiment, the body 10 and expander segments 43 are preferably formed with a left hand buttress type of threaded interconnection 41, 42, to not only provide a one-way clutching action between the body 10 and split expander 44, but also to hold the body against rotation during its disintegration by a rotary drill bit, and during unscrewing of the tubing 11.

It is, therefore, apparent that lock devices for well packers have been provided in which a far greater load or longitudinal force may be transmitted from the body 10 through the expander and slips to the casing 12, since large load or force transmitting surfaces are present and operable. Large cooperable surfaces on the body and expander are effective to transmit the load between these two members, and relatively large tapered surfaces on the expander and slips are operable to transmit the load on the body through the slips to the casing. The effective surfaces between the body and expander extend almost entirely around the body and over a substantial length; the load transmitting surfaces between

the expander and slips are also very substantial in both circumferential and tapered extent.

The large load transmitting surfaces do not tend to distort the parts and crush them inwardly, since the load transmission tending to collapse the body 10 inwardly is fairly uniformly distributed around the circumference of the body. Accordingly, relatively soft and easily drillable materials, such as magnesium, may be used for the body without impairing its ability to carry and transmit a large thrust or load safely.

The lock devices also provide the desirable feature of allowing easy upward ratcheting of the body 10 relative to the expander 22 or 44 in producing anchoring of the well packer in packed off condition against the casing, while preventing relative downward movement between the body and the expander and slips 19 after the latter have been anchored against the casing. Moreover, the provision of the threaded interconnection 41, 42, between the body 10 and expander 22 or 44 and the wedging of the latter in the slips 19, which are anchored to the casing 12, provides the desirable element of holding the body against rotation in the event its removal from the well casing by a rotary drill bit becomes necessary.

Having thus described our invention, what we claim and desire to secure by Letters Patent is:

1. A well tool, including a supporting member, split expansible and contractible expander means movable with respect to said supporting member, slips movable by said supporting member along said expander means into engagement with a cooperable member, said expander means and supporting member having interengaging ratchet teeth integral with said expander means and supporting member and permitting longitudinal movement in one direction of said supporting member along said expander means in order to engage said slips with said cooperable member, said teeth locking said supporting member to said expander means upon longitudinal movement of said supporting member in the other direction, the locking surfaces of said ratchet teeth on said expander means facing in the direction in which said supporting member is movable in engaging said slips with said cooperable member, the companion locking surfaces of said supporting member ratchet teeth facing in the opposite direction.
2. A well tool adapted to be set in a well conduit, including a body, split expansible and contractible expander means slidably mounted on said body, slips movable by said body along said expander means into engagement with said conduit, said expander means and body having interengaging ratchet teeth integral with said expander means and body and permitting longitudinal movement in one direction of said body within said expander means in order to engage said slips with said conduit, said teeth locking said body to said expander means upon longitudinal movement of said body in the other direction, the locking surfaces of said ratchet teeth on said expander means facing in the direction in which said body is movable in engaging said slips with said conduit, the companion locking surfaces of said body ratchet teeth facing in the opposite direction.
3. A well tool adapted to be set in a well conduit, including a body, a split expansible and contractible expander slidably mounted on said body and having a tapered external surface, slips slidably movable by said body along said tapered surface into engagement with said conduit, said ex-

pander and body having interengaging ratchet teeth integral with said expander and body and permitting longitudinal movement in one direction of said body within said expander in order to engage said slips with said conduit, said teeth locking said body to said expander upon longitudinal movement of said body in the other direction, the locking surfaces of said ratchet teeth on said expander facing in the direction in which said body is movable in engaging said slips with said conduit, the companion locking surfaces of said body ratchet teeth facing in the opposite direction.

4. A well tool adapted to be set in a well conduit, including a body, a split expandable and contractible expander slidably mounted on said body and having an external converging surface, interengaging ratchet teeth on said body and in said expander integral with said body and expander for locking said body and expander together upon movement of said body in one longitudinal direction and for permitting movement of said body in the other longitudinal direction relative to said expander, the locking surfaces of said ratchet teeth on said body facing in the direction in which said external surface converges and the locking surfaces of said ratchet teeth in said expander facing in the direction in which said surface diverges, and slips slidable along the surface of said expander into engagement with said conduit and operable to force said expander inwardly to maintain the interengagement of said ratchet teeth.

5. A well tool adapted to be set in a well conduit, including a body, a split expandable and contractible expander slidably mounted on said body and having an external downwardly converging surface, ratchet teeth on and integral with said body having downwardly facing locking surfaces, ratchet teeth in and integral with said expander having upwardly facing locking surfaces which are engageable with said downwardly facing surfaces of said body ratchet teeth, and slips slidable along the surface of said expander into engagement with said conduit and operable to force said expander inwardly to maintain said ratchet teeth interengaged.

6. A well tool adapted to be set in a well conduit, including a body, a split expander slidably mounted on said body and having an external downwardly converging surface, a downwardly facing buttress left hand thread on said body, an upwardly facing buttress left hand thread in said expander engageable with said body thread, and slips slidable along the surface of said expander into engagement with said conduit and operable to force said expander inwardly to maintain said threads interengaged.

7. A well tool adapted to be set in a well conduit, including a body, a split expander slidably mounted on said body and having an external converging surface, a buttress left hand thread on said body facing in the direction in which said external surface converges, a buttress left hand thread in said expander engageable with said body thread and facing in the direction in which said external surface diverges, and slips slidable along the surface of said expander into engagement with said conduit and operable to force said expander inwardly to maintain said threads interengaged.

8. A well tool, including a supporting member, a split expander slidable along said supporting member and having a converging surface, said supporting member having a buttress left hand

5 thread facing in one longitudinal direction, said expander having a buttress left hand thread engageable with said supporting member thread and facing in the other longitudinal direction, and slips slidable along said expander surface into engagement with a cooperable member and operable to force said expander laterally to maintain said threads interengaged.

9. A well tool, including a supporting member, a split expander slidable along said supporting member and having a converging surface, said supporting member having a thread, said expander having a thread engageable with said supporting member thread, and slips slidable along said expander surface into engagement with a cooperable member and operable to force said expander laterally to maintain said threads interengaged, said threads wedging said expander more firmly into said slips upon application of turning effort to said supporting member in one direction.

10. A well tool, including a supporting member, expander means movable with respect to said supporting member, said expander means comprising longitudinally extending segments separate from each other and a ring separate from said segments, coengaging means on said segments and ring coupling said segments together for joint longitudinal movement while permitting their lateral movement, said supporting member and segments having interengaging ratchet threads, and slips movable along said segments into engagement with a cooperable member and operable to force said segments bodily laterally and firmly against said supporting member to maintain said threads interengaged.

11. A well tool adapted to be set in a well conduit, including a body, expander means movable on said body, said expander means comprising longitudinally extending segments separate from each other and a ring separate from said segments, coengaging means on said segments and ring coupling said segments together for joint longitudinal movement while permitting their lateral movement, said body and segments having interengaging ratchet threads, and slips movable along said segments into engagement with said conduit and operable to force said segments bodily inward against said body to maintain said threads interengaged.

12. A well tool adapted to be set in a well conduit, including a body, an expander mounted on said body, slips cooperable with said expander and engageable with said conduit to prevent movement of said body in one longitudinal direction, a split expandable and contractible expander mounted on said body, slips movable by said body along said split expander and into engagement with said conduit to prevent longitudinal movement of said body in the other direction, interengaging ratchet teeth on said body and split expander integral with said body and split expander and permitting longitudinal movement in one direction of said body within said split expander in order to engage said slips with said conduit, said teeth locking said body to said split expander upon longitudinal movement of said body in the other direction the locking surfaces of said ratchet teeth on said expander facing in the direction in which said body is movable in engaging said slips with said conduit, the companion locking surfaces of said body ratchet teeth facing in the opposite direction.

13. In a well tool adapted to be set in a well conduit, including a body, an upper expander

slidably mounted on said body and having an external upwardly converging surface, upper slips slideable on said surface into engagement with said conduit, a split expandable and contractible lower expander slidably mounted on said body and having an external downwardly converging surface, slips slideable by said body along said split expander surface into engagement with said conduit, said split expander and body having inter-engaging ratchet teeth integral with said split expander and body and permitting upward movement of said body within said split expander in order to move said lower slips into engagement with said conduit, said teeth locking said body to said split expander upon downward movement of said body, the locking surfaces of said body ratchet teeth facing downwardly, the locking surfaces of said expander ratchet teeth facing upwardly.

14. A well tool, including a supporting member, expandable means movable with respect to said supporting member, said expandable means comprising longitudinally extending segments separate from each other and a ring separate from said segments, coengaging means on said segments and ring coupling said segments together for joint longitudinal movement while permitting their lateral movement, and slips movable along said segments into engagement with a cooperable member and operable to force said segments

15

20

bodily laterally and firmly against said supporting member.

15. A well tool adapted to be set in a well conduit, including a body, expander means movable on said body, said expander means comprising longitudinally extending segments separate from each other and a ring separate from said segments, coengaging means on said segments and ring coupling said segments together for joint longitudinal movement while permitting their lateral movement, and slips movable along said segments into engagement with said conduit and operable to force said segments bodily inwardly against said body.
